UNITED STATES PATENT OFFICE

99,250

DESIGN FOR LACE

Oscar F. Schicker, Teaneck, N. J.

Application January 18, 1936, Serial No. 60,649

Term of patent 7 years

To all whom it may concern:

Be it known that I, Oscar F. Schicker, a citizen of the United States of America and residing at Teaneck, in the county of Bergen and State of New Jersey, have invented a new, original, and ornamental Design for Lace, of which the following is a specification, reference being had to the accompanying drawing, forming a part thereof.

The drawing is a view of lace showing my new design, and for the purpose of bringing out the design it is shown against a black background.

I claim:

The ornamental design for lace as shown and described.

This specification signed this 17th day of January, 1936.

OSCAR F. SCHICKER.
